UNITED STATES PATENT OFFICE

ANDREW McNALLY, OF CHICAGO, ILLINOIS.

OIL-CAN.

SPECIFICATION forming part of Letters Patent No. 350,939, dated October 19, 1886.

Application filed August 7, 1886. Serial No. 210,260. (No model.)

To all whom it may concern:

Be it known that I, ANDREW McNALLY, of Chicago, in the county of Cook and State of Illinois, have invented certain new and useful 5 Improvements in Oil-Cans, of which the following is a description, reference being had to the accompanying drawings, in which—

Figure 1 is a side elevation of said can, and Fig. 2 is a central vertical sectional view of 10 the upper portion of said can.

Like letters of reference indicate like parts in the different figures.

The object of my invention is to provide a cheap and simple automatic or self-closing can 15 for holding kerosene, naphtha, and other similar oils or fluids, which are so volatile or combustible as to render them liable to ignition in case they are kept in an open can or one closed with a removable stopper, in the usual way. I 20 accomplish said object substantially in the manner hereinafter more particularly described and claimed.

In the drawings, A represents an ordinary metal can, provided with a cone-shaped top, 25 A', and handle B, rigidly attached thereto in any well-known way. Said can is provided with an interior annular flange, a, the under side of which is preferably convex, as shown.

Attached to the outside of the can, and projecting above it, I provide a screw-nozzle, a', Fig. 2, to which is attached by means of a screw a removable spout, a''. Near the top of the can I solder or otherwise rigidly attach a small vertical tube, C, which communicates 35 with the interior of the can through a suitable opening, c, Fig. 2. Inserted within said tube is a rod, D, having a bent portion, D', which is projected within the can and bent upwardly at its center, as shown. Upon the upper end 40 of said rod is rigidly attached a valve, E, the edges of which are made concave to fit the convex surface of the flange a. A secondary valve, E', is also attached to said rod at the point

of its insertion within the can, said valve being placed obliquely to the vertical axis of the 45 rod D, so as to conform to the shape of the can and cover the opening c. A spiral spring, c', is placed around the tube and rod D, so as to press upwardly upon the latter and retain it normally in the position shown in Fig. 2, 50 which, it is obvious, must retain the valve E firmly against its seat. Said rod D is bent back in line with the handle, and a portion, D'', is then bent downwardly parallel with the part D, so as to project through a hole, b, in said 55 handle. Thus the part D'' serves as a guide and prevents the valve E from moving laterally, and thus causing it to be displaced from its seat. A thumb-piece, d, is soldered to the top of the wire, as shown, so that upon grasping 60 the handle B and pressing downwardly upon said thumb-piece the valves E and E' are displaced, as shown in dotted lines in Fig. 2, which permits the liquid to be poured from the nozzle. Upon releasing said pressure the 65 spring acts upon the rod and returns the valves to their normal positions, respectively.

I am aware that cans have been made in which levers have been used to operate the valves which close the eduction and vent openings, said levers being held normally in a given position by means of one or more springs, and I make no claim to such construction.

What I do claim is—

An oil-can having an interior valve-seat, a, in combination with the rod D, having extensions D' D'', the latter extending downwardly through a perforation in the handle, tube C, made larger than the rod, spring c', and valves 80 E', constructed and arranged substantially as described, and for the purposes set forth.

ANDREW McNALLY.
